UNITED STATES PATENT OFFICE.

JOHN PORIS, OF OSHKOSH, WISCONSIN.

STOVE-CASING.

1,360,314.

Specification of Letters Patent. Patented Nov. 30, 1920.

Application filed November 8, 1919. Serial No. 336,639.

To all whom it may concern:

Be it known that I, JOHN PORIS, a citizen of Greece, and resident of Oshkosh, in the county of Winnebago and State of Wisconsin, have invented new and useful Improvements in Stove-Casing, of which the following is a description, reference being had to the accompanying drawings, which are a part of this specification.

10 The present invention relates to certain new and useful improvements in heating devices and refers more particularly to a stove casing.

One object of the present invention is to 15 provide means whereby a single stove of the ordinary room type may be readily utilized to provide heat for a plurality of rooms.

Another object of my invention is to provide a frame including a plurality of sections adapted to be set in a wall at the 20 point of intersection between several rooms and having means extending into each room to provide a heat chamber within the frame in which the heating stove is adapted to be 25 placed.

A further object of this invention is to provide a device of the type described having means for supplying heat to the rooms directly communicating with the heat chamber and to rooms at a remote point.

With the above and other objects in view which will appear as the description proceeds, my invention resides in the novel construction, combination and arrangement of 35 parts, substantially as hereinafter described and more particularly defined by the appended claims, it being understood that such changes in the precise embodiment of the hereindisclosed invention may be made as 40 come within the scope of the claims.

In the accompanying drawings I have illustrated one complete example of the physical embodiment of my invention constructed according to the best mode I have 45 so far devised for the practical application of the principles thereof, and in which:

Figure 1 is a top plan view of my invention illustrating the same as positioned at the intersection point of the walls of a 50 building.

Fig. 2 is a perspective view of a corner of a room at the wall intersection illustrating my invention as set in the wall.

Fig. 3 is a front plan view of one of the 55 doors closing the heating chamber from the room.

Fig. 4 is an enlarged detail sectional view taken through the upper portion of the door on the line 4—4 of Fig. 3.

Fig. 5 is an enlarged fragmentary perspective view of one of the regulating shutters I employ for controlling the egress of heat from the heat chamber through the doors.

Fig. 6 is a fragmentary view, partly in 65 section and partly in elevation, of the means I employ for maintaining the door shutters in the desired adjusted position.

Fig. 7 is a transverse sectional view taken through one of the doors on the line 7—7 70 of Fig. 3.

Fig. 8 is a perspective view of a portion of the upper half of the frame structure, parts being removed and parts being broken away and in section to more clearly illustrate details of construction.

Fig. 9 is an enlarged sectional view taken through the upper half of one of the frame sections to illustrate the novel manner of securing the upper closure parts in position, 80 said view being taken on the line 9—9 of Fig. 8.

Fig. 10 is a perspective view of my frame structure parts being removed and parts being broken away and in section to more 85 clearly illustrate sectional details.

Fig. 11 is a fragmentary view of the interlocking connection between the frame sections, parts being broken away and in section, and

Fig. 12 is a sectional view taken through Fig. 11 on the line 12—12.

My invention is designed for use in adapting an ordinary coal stove for heating a plurality of rooms and is designed to be disposed within a recess formed at the point of intersection of the plurality of walls 15 defining the rooms 16 and embodies two rectangular frame structures 17 and 18 adapted to be fitted within the recess. For the purpose of safety several bricks of asbestos or the like 19 insulate the frames from the wall.

The frame 17 is formed of a single length of tubular metal bent to form a rectangle and the frame 18 is also formed of tubular metal, but is in two sections, 20 and 21, having their ends in locking engagement with the frame 17 as will be later described. Carried by each adjacent frame section is an upper segmental plate 22 and a lower segmental plate 23 to form that part of the heating chamber between the frame struc-

ture which projects into each room 16 and each extension of the heating chamber is inclosed by a pair of doors 24 hingedly connected as at 25 to the frame sections. The 5 doors of each adjacent pair are normally retained in closed position by means of suitable catch or other fastening means 26 and have formed centrally therein an opening 10 closed by an adjustable panel shutter 27 for controlling the egress of air from the heat chamber.

As best shown by dotted lines in Fig. 1 the heating stove 28, is positioned within the heating chamber formed by the frame 15 structure and the doors 24, and when it is desired to heat any one of the rooms 16 the shutters 27 of the doors communicating therewith are opened and when it is desired to heat the upper rooms of the house (not 20 shown) the heat is conducted thereto by means of pipes or other conductors 29 leading from out of the upper plates 22. Air is admitted into the heating chamber to provide draft means for the stove 28 through a 25 damper 30 in each door 24. In the event that coal gases should accumulate within the heating chamber about the stove 28, I provide safety valves 31 so that the same may readily pass outwardly of the heating chamber 30 should the pressure of such gases become excessive. The stove pipe 32 of the stove 28 passes through one of the upper plates 22 to its point of discharge, as best shown in Fig. 1.

35 The frame sections 20 and 21 have their ends reduced as at 33 and provided with recesses 34, which ends project into openings 35 within the frame section 17 and engage a positioning block 36 carried by the section 40 17 centrally of each pair of openings 35 as best shown in Figs. 11 and 12. The lower transverse portions of the sections 17, 20 and 21 are slightly recessed or grooved as at 37 to provide positioning means for receiving the bottom plates 23.

The upper plates 22 are held in place by means of binding jack screws 38 carried by a threaded wing block 39 as best shown in Figs. 8, 9 and 10. For convenience in securing the hinges 25 to the frame sections 50 openings 40 are formed therein for convenience in holding the locking nuts 41 for securing the hinges in place and each of these openings is normally closed by a removable plate 42, the lower plates 42 being held in place by wing nuts 43 and the upper plates 42 are held in place by means of the wing blocks 39 having threaded engagement with T-head bolts 44 which engage the inner side 55 of the frame section and thus firmly secure the plate in position. The plates 22 are firmly secured between the ends of the jack screws 38 and the adjacent sections as best 60 shown in Figs. 8 and 9. The plates 32 have 65 their inner ends secured in place by a cen-

tering block 45 carried by a securing bolt 46 also serving to secure the block 36 in position.

The panels 27 each include a plurality of medially pivoted sections 47 having inwardly extending arms 48 whereby the sections of each panel may be pivotally connected together by means of connecting rods 49 and the lowermost section of each panel is pivotally connected by means of links 50 75 with an operating lever 51. The lever 51 is provided with a plurality of notches 52 in engagement with the edge of the door 24 adjacent the opening 53 through which it passes whereby the sections 47 may be maintained in any desired adjusted position. In order that a snug fit may be had when the panel sections 47 are in closed position, the upper edge of each section is recessed as at 54 to receive the lower edge 55 of the section 80 thereabove and to prevent the passage of the heated gases along the sides of the sections when closed, strips 56 are pivotally connected therewith and are adapted to cover the adjacent sides of the sections 47 85 and the adjacent side of the door 25 as best shown in Figs. 3, 4 and 5.

From the foregoing description taken in connection with the accompanying drawings, it will be at once apparent I provide a 90 heating furnace which will be capable of use with the ordinary heating stove now in general use to adapt the same for heating several adjoining rooms.

What I claim for my invention is:

1. A device of the class described comprising a knockdown frame adapted to be set in a recess formed in a wall structure at an intersection point between several rooms, segmental plates detachably secured to the 105 frame and projecting into the rooms to define heating chambers, and doors closing the chambers.

2. A device of the class described comprising a knockdown frame adapted to be 110 set in a recess formed in a wall structure at an intersection point between several rooms and including a plurality of interlocking sections, top and bottom plates carried by the frame sections to provide a chamber projecting into each room, and doors closing the chamber.

3. A device of the class described comprising a knockdown frame adapted to be 115 set in a recess formed in a wall structure at an intersection point between several rooms and including a plurality of interlocking sections, top and bottom plates carried by adjacent frame sections to provide a heating chamber projecting into each room, 120 doors closing the heating chamber, and shutters for adjustably regulating the passage of heat into each room.

4. A device of the class described comprising a knockdown frame adapted to be 125

set in a recess formed in a wall structure at an intersection point between several rooms and including a plurality of interlocking sections, top and bottom plates carried by adjacent frame sections to provide a heating chamber projecting into each room, doors closing the heating chamber, shutters for adjustably regulating the passage of heat into each room, and a duct leading from the heating chamber.

5. A device of the class described comprising a knockdown frame including tubular sections adapted to be set in a recess formed in a wall structure at an intersection point between several rooms, interlocking connections between the frame sections, said frame defining a chamber for receiving a heating stove, upper and lower plates carried by adjacent frame sections and providing means for extending the chamber into each room, doors carried by the frame sections, and means in the doors for adjustably

regulating the egress of heat from the chamber into the rooms.

6. A device of the class described comprising a knockdown frame including tubular sections adapted to be set in a recess formed in a wall structure at an intersection point between several rooms, interlocking connections between the frame sections, said frame defining a chamber for receiving a heating stove, upper and lower plates carried by adjacent frame sections and providing means for extending the chamber into each room, clamping means for securing the upper plates in position, doors carried by the frame sections, and means in the doors for adjustably regulating the egress of heat from the chamber into the rooms.

10 15 20 25 30 35 40

In testimony whereof, I affix my signature.

JOHN PORIS.
